SHORE HEAD STRUCTURE

Arthur H. Symons, Chicago, Ill., assignor to
 Symons Clamp & Mfg. Company, Chicago, Ill.,
 a corporation of Delaware

Application March 11, 1943, Serial No. 478,768

5 Claims. (Cl. 248—357)

The present invention relates generally to head structures for shores. More particularly the invention relates to that type of head structure which is designed releasably to connect a T-head or L-head type of crossbar to the upper end of the shore and comprises a pair of brackets, one of which is fixedly connected to the upper end of the shore and has a flat, rectangular bearing surface at the top thereof and the other of which is shaped and adapted to receive and retain the crossbar and has an elongated, flat bearing surface at the bottom thereof for engaging the flat bearing surface at the top of the one bracket, and also has means for releasably securing or connecting it to said one bracket.

One object of the invention is to provide a shore head structure of this type which is an improvement upon, and has certain advantages over, previously designed head structures of like character and is characterized by the fact that the crossbar receiving and retaining bracket may be quickly and readily connected to, and released from, the fixed bracket at the upper end of the shore.

Another object of the invention is to provide a shore head structure of the type under consideration in which the means for releasably connecting the crossbar receiving bracket to the fixed bracket at the upper end of the shore comprises a hook which is connected to, and depends from, one end of the crossbar receiving bracket and is adapted to hook around and grip one end of the top wall of the fixed bracket, and additionally comprises a latch which depends from the other end of the crossbar receiving bracket and is pivotally arranged so that it may be turned into or out of latched relation with the other end of the top wall of the fixed bracket.

A further object of the invention is to provide a shore head structure of the type and character under consideration in which the two brackets have interlocking means whereby they are effectively held against lateral displacement when they are in connected relation.

A still further object of the invention is to provide a shore head structure which is generally of new and improved construction and is so designed that it may be manufactured or produced at a low and reasonable cost.

Other objects of the invention and the various advantages and characteristics of the present shore head will be apparent from a consideration of the following detailed description.

The invention consists in the several novel features which are hereinafter set forth and

are more particularly defined by claims at the conclusion hereof.

In the drawing which accompanies and forms a part of this specification or disclosure and in which like numerals of reference denote corresponding parts throughout the several views:

Figure 1 is a fragmentary perspective of a shore having a head structure embodying the invention;

Figure 2 is a bottom perspective of the crossbar receiving and retaining bracket constituting one part of the head structure;

Figure 3 is a top perspective of the fixed bracket constituting the other part of the structure; and

Figure 4 is a longitudinal section of the two brackets illustrating in detail the manner in which the crossbar receiving and retaining bracket is connected to the fixed bracket at the upper end of the shore.

The head structure which is shown in the drawing constitutes the preferred form or embodiment of the invention. It is illustrated in connection with, and serves as the head part of, a shore 5. The latter consists of a pair of laterally spaced parallel upstanding timbers 6 and serves in connection with the head structure as a medium for use in building construction. The lower end of the shore 5 is provided with any suitable adjusting means (not shown) so that it may be raised or lowered to the desired extent. The head structure forming the subject matter of the invention consists of a pair of brackets 7 and 8 and is designed, as hereinafter described more in detail, releasably to connect a T-head or L-head type crossbar 9 to the upper end of the shore 5.

The bracket 7 is preferably in the form of a one-piece metal casting and comprises a pair of parallel, spaced apart, oppositely facing side walls 10, a pair of parallel, spaced apart, oppositely facing end walls 11, and a rectangular top wall 12. The end walls 11 extend between, and are connected to, the ends of the side walls 10 and define with the side walls and the top wall 12 a downwardly facing socket for the upper ends of the timbers 6 constituting the shore 5. The top wall 12 is flat and forms a bearing surface on which the bracket 8 is adapted to rest. The ends of the top wall 12 of the bracket 7 project beyond or outwards of the end walls 11 and are of reduced width. Triangular webs 13 serve to brace or reinforce the outwardly projecting ends of the top wall 12 of the bracket 7. These webs are formed integrally with, and

underlie, the end portions of the side margins of said top wall and are joined to, and formed integrally with, the ends of the end walls 11. The ends of the side walls 10 of the bracket 7 are disposed outwards of the webs 13 and form shoulders 14. The end walls 11 of the bracket 7 have holes 15 therein for accommodating bolts 16. The latter extend through the holes 15 and aligned holes in the upper ends of the timbers 6 and serve fixedly to secure the bracket 7 to the upper end of the shore 5. The central portion of the top wall 12 of the bracket 7 is provided with a circular hole 12^a and this, as shown in Figure 4, is located between said upper ends of the shore forming timbers 6.

The bracket 8, like the bracket 7, is preferably in the form of a metal casting. It is shaped to receive the crossbar 9 and comprises an elongated rectangular bottom wall 17 and a pair of upstanding side walls 18. The bottom wall 17 is appreciably longer than the top wall 12 of the fixed bracket 7 at the upper end of the shore and has a flat bottom face, the central portion of which is adapted to rest upon the top wall 12 of the bracket 7 when the two brackets are in their operative or connected position. The side walls 18 of the bracket 8 are substantially coextensive with, and are joined to, the side margins of the bottom wall 17. They are spaced apart a distance corresponding to the width of the crossbar 9. The crossbar, as shown in Figures 1 and 4, fits between the side walls 18 of the bracket 8 and rests upon the top face of the bottom wall 17. Lag screws 19 serve fixedly to connect the crossbar 9 to the bracket 8 and these screws extend upwards through holes 20 in the ends of the bottom wall 17. The bottom wall 17 of the bracket 8 is of uniform width from end to end and corresponds in width to the central portion of the top wall 12 of the bracket 7. The holes 20 for the lag screws 19 are so positioned or located that they are disposed outwards of the ends of the top wall 12 of the bracket 7 when the two brackets are in connected relation.

In addition to the brackets 7 and 8 the head structure for the shore 5 comprises releasable means for connecting the two brackets together. This means comprises a pair of hooks 21 at one end of the bottom wall 17 of the bracket 8 and a pivot type latch 22 at the other end of said bottom wall 17. The hooks 21 are formed integrally with, and depend from, the bottom wall 17. They face or project inwards and are adapted to hook around and grip the adjacent end of the top wall 12 of the bracket 7 when the bracket 8 is in place on the bracket 7, as shown in Figures 1 and 4. The latch 22 is in the form of a cast metal arm and is pivotally supported by way of a bolt 23. The latter extends through a hole in the central portion of the latch and a hole 24 in the bottom wall 17 of the bracket 8. It is preferably arranged so that the head thereof is at the top and carries a nut 25 at the lower end of its shank. The bolt 23 permits the latch to turn or rotate in a plane that is parallel to the bottom wall 17. One end of the latch 22 has a convex upper surface and is adapted when the two brackets 7 and 8 are in engagement with one another to underlie the adjacent end of the top wall 12 of the bracket 7 and thus lock the two brackets together. The other end of the latch 22 is in the form of a finger piece which permits the latch to be gripped in connection with turning or rotation thereof. When the latch is turned so as to swing the end with the

convex upper surface out of engagement with the adjacent end of the top wall 12 of the bracket 7 the bracket 8 is released and hence may be disconnected from the bracket 7. A split washer 26 is mounted on the shank of the bolt 23 between the nut 25 and the central portion of the latch 22 and serves yieldingly to urge the latch upwards towards the bottom wall 17 of the bracket 8. For the purpose of preventing lateral displacement of the bracket 8 relatively to the bracket 7 when the two brackets are in connected relation the bracket 8 is provided with a pair of depending lugs 27 and a pair of depending lugs 28. These lugs are formed integrally with, and depend from, the side margins of the bottom wall 17 of the bracket 8. The lugs 27 are located directly inwards of the hooks 21 and are adapted to straddle the adjacent reduced end of the top wall 12 of the bracket 7 when the bracket 8 is in place on the bracket 7. The other lugs, that is, the lugs 28, are located inwards of the latch 22 and are adapted to straddle the adjacent reduced end of the top wall 12, as shown in Figure 1. The lugs 27 and 28 are so positioned that when the two brackets are in connected relation they abut against the shoulders 14 at the ends of the side walls 10 of the bracket 7. In order properly to center the bracket 8 with respect to the bracket 7 when the bracket 8 is applied to the bracket 7 the bracket 8 is provided with a depending annular flange 29. This flange is formed integrally with the central portion of the bottom wall 17 of the bracket 8 and is adapted to fit within the circular hole 12^a in the central portion of the top wall 12 of the bracket 7, as shown in Figure 4. When the flange 29 is disposed in the hole 12^a it assists the lugs 27 and 28 in preventing lateral displacement of the bracket 8 with respect to the bracket 7.

When it is desired to apply the crossbar 9 to the upper end of the shore 5 the latch 22 is turned or rotated into a position wherein it extends reversely to the bracket 8. Such bracket is then positioned angularly in order to bring the hooks 21 into hooked relation with the adjacent end of the top wall 12 of the bracket 7, as shown in Figure 4. After the hooks are brought into hooked relation with such end of the top wall 12 the bracket 8 is swung downwards into a position wherein the bottom wall 17 thereof fits flatly against the top surface of the top wall 12 of the bracket 7. In connection with downward swinging of the bracket 8 the annular downwardly tapered flange 29 enters the hole 12^a and the lugs 27 and 28 are brought into straddled relation with the reduced ends of the top wall 12 of the bracket 7. After the bracket 8 is swung into place the latch 22 is turned so as to bring the end with the convex upper face into a position wherein it underlies the adjacent end of the top wall 12. Because of the convex surface on such end of the latch and the fact that the latch is urged upwards by the split washer 26 the latch grips the adjacent end of the top wall 12 with upward pressure. When it is desired to remove the crossbar 9 from the upper end of the shore 5 it is only necessary to turn the latch 22 out of gripping relation with the adjacent end of the top wall 12 of the bracket 7 and then swing the bracket 8 upwards and manipulate it out of hooked relation with the bracket 7.

The herein described shore head structure is essentially simple in design and hence it is capable of being produced at a low and reasonable cost. It may be quickly and readily assembled

or dismantled because of the arrangement of the brackets 1 and 8 and is characterized by the fact that the two brackets when in connected relation are effectively and efficiently held against side-wise or longitudinal displacement one relatively to the other.

The invention is not to be understood as restricted to the details set forth since these may be modified within the scope of the appended claims without departing from the spirit and scope of the invention.

Having thus described the invention what I claim as new and desire to secure by Letters Patent is:

1. A head structure for a shore, comprising a bracket provided with means for connection to the upper end of the shore and having a top wall with two opposed marginal portions thereof projecting outwards, and a second bracket adapted to receive and retain a crossbar and embodying a bottom wall adapted to rest upon the top wall of the first mentioned bracket and provided on the under side thereof with a depending hook for engaging one of said marginal portions of the top wall, and in addition a movably mounted latch for gripping the other marginal portion of said top wall and releasably connecting the two brackets together.

2. A head structure for a shore, comprising a bracket provided with means for connection to the upper end of the shore and embodying a flat, rectangular top wall with the ends thereof free, and a second bracket shaped to receive and retain a crossbar and embodying a bottom wall adapted to rest upon the top wall of the first mentioned bracket and provided at one portion thereof with means for interlocking with one end of said top wall and at another portion thereof with a depending pivot type latch for gripping the other end of said top wall and releasably connecting the two brackets together.

3. A head structure for a shore, comprising a bracket provided with means for connection to the upper end of the shore and having a flat, rectangular top wall with the ends thereof free, and an elongated second bracket adapted to receive and retain a crossbar and embodying a rectangular bottom wall adapted to rest upon, and extend lengthwise of, the top wall of the first mentioned bracket and provided at one end thereof with a depending hook for engaging and gripping one end of the top wall of said first men-

tioned bracket and at its other end with a movably mounted latch for gripping the other end of said top wall and releasably connecting the two brackets together, one of said brackets being provided with side lugs adapted when the two brackets are in connected relation to straddle the other bracket and prevent lateral displacement of said one bracket relatively to said other bracket.

4. A head structure for a shore, comprising a bracket provided with means for connection to the upper end of the shore, and having a flat, rectangular top wall having the ends thereof free and embodying a hole in its central portion, and an elongated second bracket adapted to receive and retain a crossbar and embodying a rectangular bottom wall adapted to rest upon, and extend lengthwise of, the top wall of the first mentioned bracket, provided at one end thereof with means for interlocking with one end of said top wall and at its other end with a movably mounted latch for gripping the other end of said top wall and releasably connecting the two brackets together, and also provided at the central portion thereof with a depending protuberance adapted to fit within said hole and center said bottom wall with respect to the top wall.

5. A head structure for a shore, comprising a bracket provided with means for connection to the upper end of the shore, and having a flat, rectangular top wall having the ends thereof free and embodying a hole in its central portion, and an elongated second bracket adapted to receive and retain a crossbar and embodying a rectangular bottom wall adapted to rest upon, and extend lengthwise of, the top wall of the first mentioned bracket, provided at one end thereof with means for interlocking with one end of said top wall and at its other end with a movably mounted latch for gripping the other end of said top wall and releasably connecting the two brackets together, and also provided at the central portion thereof with a depending protuberance adapted to fit within said hole and center said bottom wall with respect to the top wall, one of said brackets being provided with side lugs adapted when the two brackets are in connected relation to straddle the other bracket and prevent lateral displacement of said one bracket relatively to said other bracket.

ARTHUR H. SYMONS.
